US00D566071S

(12) **United States Design Patent** (10) Patent No.: **US D566,071 S**
(45) Date of Patent: **** Apr. 8, 2008**

(54) **PORTABLE GLOBAL POSITIONING SYSTEM**

(75) Inventor: **Takuji Kaneko**, Daito (JP)

(73) Assignee: **Funai Electric Company Limited**,
Osaka (JP)

(**) Term: **14 Years**

(21) Appl. No.: **29/281,368**

(22) Filed: **Jun. 21, 2007**

(30) **Foreign Application Priority Data**

Feb. 1, 2007 (JP) 2007-002166

(51) **LOC (8) Cl.** **14-03**

(52) **U.S. Cl.** **D14/126; D14/129**
